UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRIC SWITCH.

Application filed September 29, 1919. Serial No. 327,055.

To all whom it may concern:

Be it known that I, REUBEN B. BENJAMIN, a citizen of the United States, residing at Chicago, in the county of Cook and State of Illinois, have invented new and useful Improvements in Electric Switches, of which the following is a full, clear, concise, and exact description, reference being had to the accompanying drawing, forming a part of this specification.

My invention relates to electric switches, and more particularly to pull snap switch sockets.

One of the objects of my invention is to provide such a device which will be simple in construction, cheap to manufacture and durable and efficient in use.

A further object of my invention is to provide an improved compact pull snap switch mechanism which can be conveniently located in a socket.

Further objects will appear from the detailed description to follow and from the appended claims.

25 In the drawings in which one embodiment of my invention is shown:

Fig. 1 is a plan view of a pull snap switch socket embodying my invention, the cap being removed;

30 Fig. 2 is a section on the line 2—2 of Fig. 1;

Fig. 3 is a section on the line 3—3 of Fig. 2;

35 Fig. 4 is a section on the line 4—4 of Fig. 1;

Fig. 5 is a section on the line 5—5 of Fig. 1;

Fig. 6 is a section on the line 6—6 of Fig. 1;

40 Fig. 7 is a section on the line 7—7 of Fig. 5;

Fig. 8 is a section on the line 8—8 of Fig. 7;

45 Fig. 9 is a side elevation of a part of the switch mechanism;

Fig. 10 is a detail perspective view of the part of the switch shown in Fig. 9;

Fig. 11 is a detail perspective view of the switch lever;

50 Fig. 12 is a perspective view of the rotatable brushes;

Fig. 13 is a perspective view of the switch plate;

55 Fig. 14 is a perspective view of the switch frame; and

Fig. 15 is a perspective view of a spring holding member.

In order to give a general idea of the invention, it is here stated that the switch mechanism shown is of the ratchet snap switch type, that is to say, the switch mechanism is actuated by a pull member, which operates the ratchet, so that a pull on the switch will throw the switch to closed position, and the succeeding pull on the switch will throw the switch to open position, the switch mechanism being provided with a releasable detent or trip plate, which holds the switch mechanism until a considerable spring pressure has accumulated and then releases the switch mechanism.

In such switch mechanism two springs are usually provided, one for returning the ratchet after it has been operated by the pull chain, and one for accumulating energy to cause the snap action of the switch.

Referring now to the drawings in detail, the pull snap switch socket shown comprises an insulating base 20 for supporting the shell and center contacts 21 and 22, the 80 wiring terminals 23 and 24, for the shell and center contacts respectively, and the switch mechanism 25, which controls the circuit between the wiring terminal 24 and the center contact 22. The threaded shell contact 21 is 85 electrically connected with the wiring terminal 23 (Fig. 5) by means of a screw 26, which extends through a flange on the threaded shell contact, and is threaded into the bracket portion of the wiring terminal 90 23, the screw 26 thus serving not only to electrically connect the wiring terminal and threaded shell contact, but also to hold these parts in position on the insulating base.

The switch mechanism 25 controls the circuit between the other wiring terminal 24 and the center contact 22. This other wiring terminal 24 is electrically connected with one of the stationary spring contact fingers 27 (Fig. 6) of the switch, and the other stationary spring contact finger 28 of the switch is electrically connected with the center contact 22 by means of a screw 29, (as also shown in Fig. 6) this screw 29 serving not only to electrically connect the parts, 100 but to hold them on the insulating base 20. The stationary or fixed contacts 27 and 28 are engaged by a pair of contacts 30 which are formed integrally with the rotary contact plate 30^a, the fixed contacts 27 and 28 110

being thus electrically interconnected when the switch is closed.

Coming now to describe the switch mechanism in detail, this comprises, in addition to the stationary spring contact fingers 27 and 28, and the rotatable contact member 30^a, an oscillatable switch lever 31 (Fig. 11) to which is secured a combined bearing, spring retaining, and ratchet member 32, (as also is shown in Fig. 11). The switch mechanism comprises also a combined ratchet, spring securing and supporting, and eccentric member 34 (Fig. 10) the ratchet portion of which cooperates with the ratchet portion of the member 32. This in turn is provided with a spring 33 which returns the switch lever 31, and the spring supporting and retaining member 32. The latter cooperates with the energy storing spring 35, which causes the snap movement of the contact plate 30^a. A trip plate 36 is controlled by the eccentric portion of the member 34, and this trip plate controls the accumulation of tension in the spring 35, and controls the release of this spring to cause the snap movement of the contact plate 30^a. A switch frame 37, (Fig. 14) supports the switch shaft 38 and is provided with a plurality of stop shoulders 39, which cooperate with a stop lug 40 on the trip plate, to limit each snap movement of this trip plate (and of the contact plate 30^a) to substantially 90 degrees.

The ratchet portion of the member 32 previously referred to comprises radially extending fingers 41, the edges of which cooperate with the struck up ratchet teeth 42 on the member 34, some of these radially extending fingers being bent over the edges in the insulating disc 43 forming part of the switch lever 31, to secure the member 32 to this disc 43. One end of the lever returning spring 33 is secured in an opening 44 in the member 32, the other end of the spring being secured to a combined bearing and spring retaining member 45 (Fig. 15). This member 45 may be a sheet metal stamping, having a lug 46 struck up therefrom beneath which the end of the spring 33 is caught, and having a lug 47 struck up therefrom for engagement with any one of a number of notches 48, formed in the standard 49 of the switch frame 37, whereby the tension of the coil torsion spring 33 may be adjusted. The member 45 is provided with a notch 50 for engagement with a screw driver, whereby the member 45 may be pushed in to disengage the lug 47 from the notch 48, and whereby the member 45 may be turned to the desired position, and the lug 47 again engage with the desired one of the notches 48. The cup-shaped member 51 of the member 45 forms a bearing for the end of the shaft 38.

A chain rail 52 is secured to the disc 43, and a pull chain 53 is secured to and supported by this chain rail 52.

The cup-shaped portion 54 of the member 34 telescopes outside of the cup-shaped portion 55 of the member 32, the cup-shaped portion 55 thus forming a bearing for the member 34. The eccentric portion 56 of the member 34 works in a circular opening 57 in the trip plate. As the member 34 is rotated, the eccentric portion 56 shifts the trip plate 36 eccentrically, and moves the stop lug 40 out of engagement with one of the shoulders 39, and snap spring 35 then snaps the trip plate (together with the contact plate 30^a) through 90 degrees of movement, or until the lug 40 engages the following one of the shoulders 39. The contact plate 30^a is caused to rotate along with the trip plate 36 by the engagement of the lug 40 with a notch 58 in the contact plate, this engagement permitting the eccentric movement of the trip plate with respect to the contact plate but preventing relative rotation between the contact plate and the trip plate and causing the contact plate to rotate with the trip plate.

One end of the snap spring is secured to the lug 40 of the trip plate, the other end of the snap spring being secured to any one of plurality of lugs 59 formed integral with the member 34.

The switch frame 37 is secured in place on the insulating base 20 by means of a screw 60 (Figs. 2 and 3). The spring contact finger 27 is secured in place on the insulating base by means of a screw 61 (Fig. 6).

The circuit has been outlined in connection with the description of the construction. When the switch is in "on" position the circuit is as follows: From the wiring terminal 24 to the spring contact finger 27, and contact plate 30^a to the spring contact finger 28, and through the screw 29 to the center contact 22, thence to whatever translating device is inserted in the receptacle to the threaded shell contact 21, and from the threaded shell contact 21 through the screw 26, to the wiring terminal 23.

The operation of the switch is as follows: Assuming that the switch is in "on" position as shown and it is desired to turn it off, the pull chain 53 is pulled down, to rotate the switch lever 31 through an angle of 90 degrees. The movement of the switch lever 31 is limited to 90 degrees by engagement of the stop shoulders 62 and 63, on the insulating disc 43, with the abutment portions 64 and 65 of the insulating base. During this movement of the switch lever the member 34 is also rotated through an angle of 90 degrees by the engagement of the ratchet portions 41 of the member 32, with the ratchet portions 42 of the member 34. This rotation of the member 34 causes an eccentric movement of the trip plate 40 because of the eccentric portion 56 engaging the opening in the trip plate, and this

gradually forces the lug 40 outward until it finally frees itself from the shoulder 39 of the switch frame, when the snap spring 35 will cause this trip plate, together with the contact plate 30^a, to snap through an angle of 90 degrees, and quickly breaks the circuit at two points between the wiring terminal 24 and the center contact 22. When the pull chain 53 is released, the lever returning spring 33 will return the switch lever 31, the member 34, however, remaining stationary during this movement, the ratchet connections between the lever and member 34 permitting the lever to move without moving the member 34. The movement of the trip plate and the bracket is limited to 90 degrees by the engagement of the lug 40 with any one of the shoulders 39 on the switch frame.

If now it is desired to turn the switch to "off" position, the pull chain 63 is pulled down again, to move the switch lever 31 through another angle of 90 degrees, and to cause the trip plate 36 to be moved eccentrically, to release it from its engagement with the shoulders 39, to permit the trip plate (together with the contact plate 30^a) to snap through an angle of 90 degrees, to quickly close the circuit at two points between the wiring terminal 24 and the center contact 22.

Having thus described my invention, what I claim as new and desire to secure by Letters Patent is:

1. A switch mechanism comprising a rotatably mounted contact member, a rotatable trip member arranged to rotate with said contact member, means including a coil torsion spring for actuating said trip member and contact member, an oscillatable ratchet member, and a tubular member within said spring having an eccentric portion on one end for moving said trip member to release it and permit it to be actuated by said snap spring, said member having on the other end a ratchet portion struck up therefrom for cooperation with said oscillatable ratchet member.

2. A switch mechanism comprising a rotatable contact member, a rotatable trip member, means for rotating said trip member with said contact member, means including a coil torsion spring for actuating said trip member and contact member, a hollow spring drum surrounded by said coil torsion spring, said drum having a ratchet portion, and a unitary member having a bearing portion fitting inside said spring drum, and forming a bearing support therefor, and having a ratchet portion for engagement with the ratchet portion of the spring drum.

3. A switch mechanism comprising a rotatable contact member, a rotatable trip member means for rotating said trip mem-

ber with said contact member, means including a coil torsion spring for actuating said trip member, a hollow spring drum supporting said coil torsion spring, and a unitary member having a bearing portion fitting inside said spring drum, said spring drum having a ratchet portion, and said unitary member having arms extending radially therefrom and forming ratchet members for engagement with the ratchet member on the spring drum.

4. A switch mechanism comprising a rotatable contact member, a rotatable trip member, means for rotating said trip member with said contact member, means including a coil torsion spring for actuating said trip member, a hollow spring drum supporting said coil torsion spring, a unitary member having a bearing portion fitting inside said spring drum, said spring drum having a ratchet portion and said unitary member having arms extending radially therefrom and forming ratchet members for engagement with the ratchet member of the spring drum, and a switch lever to which said radially extending arms are secured.

5. A switch mechanism comprising a rotatable contact member, a rotatable trip member, means for rotating said trip member with said contact member, means including a coil torsion spring for actuating said trip member and contact member, a spring drum surrounded by said coil torsion spring, ratchet mechanism for actuating said spring drum, a bearing member for said spring drum, a switch shaft supporting said contact member, trip member, spring drum and bearing member, a switch lever comprising an insulating disc, lying in a plane to which said shaft is substantially perpendicular, said disc having an opening through which said shaft extends, a coil torsion spring for returning said lever, surrounding said shaft and extending through said opening and secured to said bearing member, said bearing member being secured to said disc.

6. A switch mechanism comprising a rotatable contact member, a rotatable trip member, means for rotating said trip member with said contact member, means including a snap spring for actuating said trip member and contact member, an oscillatable switch lever, a coil torsion spring for returning said switch lever, said returning spring, said oscillatable switch lever and said contact member being substantially coaxial, said switch lever comprising a disc lying in a plane to which the axis of said switch lever is substantially perpendicular, said disc having an axial opening therein, through which said returning spring extends, and a cup-shaped member secured to said disc and housing said spring.

7. A switch mechanism comprising a ro-

tatable contact member, a rotatable trip member, means for rotating said trip member with said contact member, means including a snap spring for actuating said trip member and said contact member, an oscillatable switch lever, a coil torsion spring for returning said switch lever, said returning spring, said oscillatable switch lever and said contact member being substantially coaxial, said 10 switch lever comprising a disc lying in a plane to which the axis of said switch lever is substantially perpendicular, said disc having an axial opening therein through which said returning spring extends and a cup-shaped member secured to said disc and housing said spring, said cup-shaped member having ratchet teeth extending therefrom for cooperation with a ratchet member to which the snap spring is secured.

20 8. A switch mechanism comprising a rotatable contact member, a rotatable trip member, means for rotating said trip member with said contact member, means including a snap spring for actuating said trip member and contact member, an oscillatable switch lever, a returning spring for returning said oscillatable switch lever, two telescopin 25 g sleeve members, the outer one of said sleeve members having the snap spring

sleeved upon and secured to it, the inner sleeve member supporting the switch lever and having the returning spring secured to it, said sleeve members having interengaging ratchet teeth, the inner of said sleeve members also forming a housing for the returning spring.

9. A switch mechanism comprising a rotatable contact brush member, a rotatable trip member, means for rotating said trip member with said contact member, means including a snap spring for actuating said trip member and contact member, an oscillatable switch lever, a returning spring for returning said oscillatable switch lever, and two telescopin 40 g sleeve members, one of said sleeve members having the snap spring secured to it, the other being secured to the switch lever and having the returning spring secured to it, said sleeve members having interengaging ratchet teeth, said first named sleeve 45 member forming a housing for the returning spring, and the other sleeve member having an eccentric portion for controlling the tripping of the trip member.

In witness whereof, I have hereunto sub- 50 scribed my name.

REUBEN B. BENJAMIN.
